UNITED STATES PATENT OFFICE.

JOHN E. DONALDSON, OF MONTEZUMA, INDIANA.

FENCE-POST.

SPECIFICATION forming part of Letters Patent No. 332,141, dated December 8, 1885.

Application filed August 28, 1885. Serial No. 175,575. (No model.)

To all whom it may concern:

Be it known that I, JOHN E. DONALDSON, a citizen of the United States, residing at Montezuma, in the county of Parke and State of Indiana, have invented new and useful Improvements in Fence-Posts, of which the following is a specification, reference being had to the accompanying drawings.

My invention has relation to improvements in fence-posts, and in foundation or base blocks for the same; and the novelty consists in the peculiar construction and combination, arrangement, and adaptation of the various parts for service, substantially as hereinafter fully set forth, and particularly pointed out in the claims.

It is the especial object of my invention to provide a substantial and durable fence-post, which shall be easily and cheaply manufactured and put up for use, which shall be capable of permitting the water to run off, and thus prevent the post from becoming impregnated with moisture and dampness, which can be easily and very firmly planted in the earth, and which shall be very simple in construction.

In the drawings hereto annexed, Figure 1 is a perspective view of a fence-post and foundation-block constructed in accordance with my invention. Fig. 2 is a central vertical longitudinal section of the same. Fig. 3 is a horizontal sectional view on the line *y y* of Fig. 2. Fig. 4 is an elevation showing the device for use as a gate-post.

Referring to the drawings, in which like letters of reference indicate corresponding parts in all the figures, *A* designates the post, preferably cut or formed from a piece of timber to the required shape and dimensions, substantially as shown in the figures of the drawings, and *B* designates the foundation or base block, detachably connected to the post *A*, as will be presently described, and made in the form shown, and of a suitable earth or clay, which is vitrified, as will be hereinafter fully described.

The base-block *B* is preferably made rectangular in form, and at its ends the vertical faces thereof are made inclined or sloping, as at *b*, said vertical inclined ends being joined or extended to projecting ribs or tongues *C*, arranged at each end of said foundation or base

block and on the plane of the under surface thereof, the upper surfaces of said projecting tongues being inclined downwardly and outwardly from the point where they meet the vertical inclined walls *b*, as shown at *c*. The upper face or surface of the base has an elevated plane portion, *D*, of an area equal to the dimensions of the lower end of the post *A*, or a little larger, on which said post is adapted to rest, said plane portion being arranged at about the midway of the transverse axis thereof and near one end. The upper surface of said base-block is inclined or sloped downward toward the sides and ends, in all directions from said elevated plane portion *D*, as shown at *e f*. I attach especial importance to this peculiar construction of the sloping faces of the base-block, as by such construction I am enabled to readily and effectively provide for the carrying off or discharge of water that may fall thereon, either from rain or otherwise.

The base-block is made of any suitable earth or clay and baked, fused, or vitrified by heat until it is rendered very hard and durable, said block being formed or shaped in a mold or molds or by any desired means or manner to give it the required dimensions and the shape or form above described. I do not desire to limit myself to a rectangular base or foundation block, as a circular or square or other shaped block can be employed with perhaps equal advantages, it only being necessary to provide the plane surface for the post, the lip or tongue *C*, and the sloping or inclined surfaces.

The base-block is planted or fitted in the ground so that the surface thereof will come on a line a little below the upper inclined faces thereof, as shown by the dotted line *x* in Fig. 2. The earth is packed tightly around said block and over the tongues *C*, which serve to hold the block from becoming easily displaced.

By leaving the inclined upper faces of the base-block above the surface of the ground the water from rain or otherwise falling thereon will flow therefrom down such inclined surfaces and the end walls and tongues thereof and into the ground, leaving the wooden post *A* free from danger of absorbing the water. By reason of the base-block being made of

clay or other earth and vitrified, it is unaffected by the moisture and climate, and is thus rendered very durable and strong.

I will now proceed to describe the manner of connecting and bracing the post to the foundation-block. In the lower edge and under surface of the post is provided a longitudinal bore, *h*, arranged centrally therein, and with the upper end of such bore a transverse aperture, *h'*, communicates and extends to one of the vertical surfaces of said post. Within said longitudinal bore *h* is fitted the upper threaded end of a bolt, *H*, and on the upper end of such bolt is fitted a nut, *i*, having a threaded aperture and a serrated or corrugated periphery, as at *i'*, said nut being arranged in the aperture *h'* and adapted to bear on the under wall thereof to clamp the post tightly and securely in position. The nut *i* may be turned by means of a punch, chisel, or other suitable implement inserted in the aperture *h'*, which aperture, after the post has been clamped in position, is filled or plugged with a block, as at *j*, thus wholly concealing the manner of connecting the post to the base-block. The lower end of the bolt *H* is fitted in an opening or bore, *k*, slightly enlarged at its lower end and made flaring, said bolt being arranged vertically therein, and the spaces between it and the walls of said opening filled with lead or other substance in a fused or melted state, as at *k'*, which is allowed to cool and solidify, thus firmly and rigidly holding the bolt in position.

I designate a brace-rod, arranged in an inclined position and having its ends bent at an angle, as at *m n*, and bearing against the post *A* and block *B*, respectively, as clearly shown in Figs. 1 and 2 of the drawings. Each end of the brace-rod is perforated, and through the aperture in the upper end thereof is passed one end of a tension-rod, *J*, which also passes through the post *A*, and has its ends threaded, on which are fitted nuts *J'*, adapted to bear on opposite sides of said post, the nut on the end which passes through the brace-rod *I*, bearing on said bent end thereof. The lower end of the brace-rod is secured to the foundation or base block by means a bolt, *L*, having a nut, *l*, bearing on said brace, the lower end of said bolt being secured in an aperture, *l'*, having tapering walls, and by means of lead, *l''*, in a manner similar to the way in which the bolt *H* is secured.

I attach importance to the particular manner in which the post is secured and braced to the foundation or base block, as by such construction a very secure and rigid connection is provided, which will not be affected by moisture or dampness, which causes the parts to rust and become useless in a short space of time.

In order to define the nature of the present invention, I would state that heretofore it has

been proposed to construct a fence-post having a foundation or base of stone provided with projecting teeth, which engage the post, and a screw or bolt passing through said base-block into the post and removably connected thereto, said base-block being further provided with concave portions immediately beneath the post, to permit the water to pass into the same and through the bolt-hole into the earth. This construction is objectionable, for the reason that the post is liable to absorb the water, or a portion of it passing into said concavity and bolt-hole, and the removable screw or bolt will become loose and not hold the post firmly. By carrying off the water exteriorly to the post it will not absorb the water or moisture to any degree, and by rigidly securing the connecting-bolt to the base-block, as described, and the nut in position therein, the post is not liable to become loose and move.

In the device shown in Fig. 4 the post is shown adapted for an agate-post, in which relation it possesses the same advantages and can be employed with equal facility.

Various changes in the form and proportion of parts can be made without departing from the principle of my invention, the essential features of which will be readily understood from the foregoing description, taken in connection with the drawings.

Having thus fully described my invention, what I claim as new, and desire to secure by Letters Patent, is—

1. The combination, with a post, of a foundation-block detachably secured to said post and having a plane portion and downwardly-sloping surfaces and projecting tongues *C*, arranged at each end thereof, substantially as described.

2. The combination, with a fence-post, of a foundation or base block composed of vitrified earth and detachably secured to said post, said block having a plane portion, *D*, for the post, downward-sloping upper surfaces from said plane portion to the sides and ends thereof, and projecting tongues *C* at each sloping end, substantially as described.

3. The combination of a fence-post having a bore and a transverse recess, a base-block, a bolt fitted in an aperture or hole in said block and rigidly held in position by a lead filling, and a serrated nut fitted in the transverse recess of the post and engaging the threaded end of the bolt, to lock said base-block and post together, substantially as described.

In testimony that I claim the foregoing as my own I have hereto affixed my signature in presence of two witnesses.

JOHN E. DONALDSON.
